C. CHISHOLM

LINE GAUGE FOR PRINTING FORMS

Filed Nov. 8, 1923

FIG. 1

FIG. 3

FIG. 4

FIG. 5

FIG. 6

INVENTOR
Clifton Chisholm
By Walter F. MacKlin,
ATTORNEY'S

UNITED STATES PATENT OFFICE.

CLIFTON CHISHOLM, OF CLEVELAND, OHIO, ASSIGNOR TO THE AMERICAN MULTIGRAPH CO., OF CLEVELAND, OHIO, A CORPORATION OF OHIO.

LINE GAUGE FOR PRINTING FORMS.

Application filed November 8, 1923. Serial No. 673,413.

To all whom it may concern:

Be it known that I, CLIFTON CHISHOLM, a citizen of the United States, residing at Cleveland, in the county of Cuyahoga and State of Ohio, have invented a certain new and useful Improvement in a Line Gauge for Printing Forms, of which the following is a full, clear, and exact description, reference being had to the accompanying drawings.

The object of this invention is to provide a very simple and effective means for positioning printing members on a form-holder so that one edge of the successive printing members may be in alignment. My line gauge, which effects this result, may, for instance, position printing strips which print a page form and thus provide for the accurate location of the left hand end of the lines on the printing page, or my gauges may be used for various tabulating work, if desired.

Patent No. 1,438,584 granted December 12, 1922 to The American Multigraph Company as assignee of William J. Demming shows a sheet metal form-holder wherein there are rows of struck-up buttons, each connected with the form-holder in the line of the row but having its edges disconnected transversely of the row. The disconnected edges thus overhang the general surface of the holder and provide means for retaining an inwardly flanged printing strip, which is mounted on the row of buttons and has its flanges projecting beneath their edges.

I have discovered that by taking a thin narrow strip of metal and passing it transversely of the holder just described, through the space beneath the tops of the aligned buttons and above the general surface of the plate, I may provide in a very simple form an abutment for the successive lines stopping them accurately in position. Furthermore when the holder is curved about a rotary printing member, the tendency of the inserted strip to resist flexure holds it effectively in place without requiring any special fastening means. My gauge may be readily inserted after a complete page blanket is made up, whether it is flat or mounted on a drum.

By sufficiently curving the form-holder, I may insert the gauge strip at any line desired over the top of the adjacent button in the succeeding line. By using different

lengths of gauges, lines may be accurately tabulated, if desired.

My invention is illustrated in the drawing hereof and is hereinafter more fully described. As shown in the drawing, Fig. 1 is 60 a plan of a portion of the blanket provided with my gauge for positioning embossed printing strips; Fig. 2 is a fragmentary side elevation of such blanket mounted on a printing drum; Fig. 3 is an enlarged cross- 65 section as indicated by the line 3—3 on Fig. 1; Fig. 4 is a fragmentary perspective illustrating the coaction of the blanket, embossed strip and gauge; Fig. 5 is a perspective of one of the gauge strips unapplied; Fig. 6 is 70 a fragmentary plan illustrating tabulation effected by my gauges.

As shown in the drawings, 10 indicates a suitable blanket, preferably of flexible sheet metal, having successive rows of struck-up 75 buttons 11 thereon. Each button is preferably round and has its two side edges 12 disconnected from the body of the plate, and its intervening edges connected therewith in the line of the row. Preferably these intervening edges merge with upwardly corrugated portions 13 of the plate which stiffen the plate in the direction of the row and form a support for the overlying embossed strip, as set out in Patent No. 1,438,582 80 granted December 12, 1922 to The American Multigraph Company as assignee of B. J. Craig.

The drawing shows printing strips 20, which are preferably metal members embossed with printing characters and having their edges 21 flanged inwardly. Each strip overlies and is supported by the row of buttons and the intermediate corrugations of the plate and has its flanged edges projecting 90 beneath the overhanging edges 12 of the buttons, whereby the strip is effectively held on to the blanket as fully explained in the Demming and Craig patents mentioned.

To enable the flanged strips to be readily mounted on such a blanket as described, it is desirable that they engage the buttons with sufficient freedom so that they may be readily slipped into place. Accordingly, unless otherwise held, such strips are liable 105 to become displaced longitudinally thereof driving the printing operation.

Fig. 5 illustrates my line gauge 30 which effectively positions the printing strips at one end. This line gauge is simply a thin, 110

narrow strip of spring metal, having a width slightly less than the width of the available space beneath the button head, and having a thickness slightly less than the 5 height of that space, and having a length sufficient to position the number of lines desired. Preferably various lengths of these flat strips 30 are provided so that either a whole page of lines may be gauged 10 as intended to be illustrated in Fig. 1 or portions of pages may be run in tabulated form, as illustrated in Fig. 6. The gauge strip may be readily inserted, whether the form be flat or curved, does not interfere 15 with the flexing thereof, and holds itself in position. A simple prick-punching of the embossed strips adjacent their other ends may prevent the strips shifting in the holder; or if desired the strips may be of 20 uniform length and a gauge strip inserted at their opposite end, as shown in the case of the tabulation in Fig. 6.

I claim:

1. The combination of a holder provided 25 with a row of hollow bosses, said bosses being connected with the holder in the line of the row and disconnected from the holder at edges transversely of the row, a printing strip resting on the row of bosses and having 30 depending flanges, and a gauge member extending transversely through a boss and adapted to be abutted by a flange of the strip.

2. The combination of a form-holder provided 35 with rows of hollow bosses, said bosses being connected with the holder in the line of the row and disconnected from the holder at edges transversely of the row, printing

strip resting on the rows of bosses, and a gauge member extending transversely 40 through raised bosses in different rows.

3. The combination of a sheet metal form-holder provided with rows of bosses struck therefrom, said bosses being connected with the holder in the line of the row and disconnected therefrom at opposite sides of the row, inwardly flanged printing strips resting on the rows and projecting beneath the disconnected edges of the bosses, and a flattened metal strip extending transversely 50 through aligned bosses of successive rows and movable through them.

4. The combination with flanged printing strips having inwardly projecting edges, and a flat flexible gauge strip, of a flexible 55 form-holder having thereon hollow upwardly projecting members above which the printing strips may be mounted longitudinally and beneath which the gauge strip may be mounted transversely.

5. The combination with inwardly flanged printing strips, of a sheet metal form-holder provided with longitudinal parallel rows of individual raised members on which the printing strips may lie, said raised members having transversely overhanging edges beneath which the strips may be extended, the raised members in successive rows being in transverse alignment, and a transverse gauge strip overlying the body of the holder and extending beneath the raised member in successive rows so that the flanged edge of the printing strips may abut it.

In testimony whereof, I hereunto affix my signature.

CLIFTON CHISHOLM.
